ration of Pennsylvania

Application July 19, 1938, Serial No. 220,074

8 Claims. (Cl. 206—57)

This invention relates to a package of inter-folded paper towels or the like, and more particularly to a novel combination shipping case and dispenser for interfolded paper towels.

Heretofore it has been impractical to pack more than a very small quantity of paper towels in a single shipping dispenser due to the weight resting on the edges of the bottom delivery opening. The friction caused by the withdrawal of a sheet increased with the quantity and weight of the towels until the resistance to the withdrawal of the sheet was greater than the strength of the towel which caused tearing of the latter.

We propose to reduce the friction present during withdrawal of sheets from the package and make it independent of the quantity of the towels in the package. This result is obtained by providing a box-like structure of fiberboard or the like in which one dimension, namely that between two opposed walls which contact the folded edge portions of the stack of towels, is made less than the corresponding dimension of the stack. In this way a pressure is applied to opposite sides of the package which causes the sheets or towels to sag downwardly in the middle. An additional reinforcement or friction means consisting of corrugated paper or the like, with the corrugations facing the stack, is applied to the inner surfaces of such walls, and the corrugations contact the folded edges of the towels in such a manner that such edges engage the longitudinal corrugations in parallel relation. It is obvious that should the sagging center of the package not be supported, the entire column of towels would descend to the bottom. To overcome this, we provide supporting ridges or the like at the bottom of the box on either side of the delivery opening, and consequently the sag is restricted and the towels are held from descending as a mass by the relatively narrow supporting edges of the ridges. As the towels are withdrawn, the support pressure is reduced, the sag is increased, and the entire column of towels descends until equilibrium is again established.

The details of the invention will now be explained in connection with the accompanying drawing, in which

Fig. 1 is a perspective view of our improved package.

Fig. 2 is a vertical sectional view taken on the line 2—2 of Fig. 1.

Fig. 3 is an enlarged section view of a detail.

Referring to the drawing, 4 designates a combined shipping and dispensing case, and 5 a stack 55 of towels arranged therein.

In accordance with the invention, the case may be made of any suitable relatively stiff or rigid material, but we prefer to make it from a fiberboard blank. Such blank is cut and folded so as to provide a top 6 having depending flaps 7 at the ends thereof (only one being shown in the drawing).

The front wall 8 and the rear wall 9 depend from the top and each of these walls is provided with flaps 10 which when brought together form 10 the side walls of the case. The flaps 10 are secured to the flaps 7 by any suitable means such as staples 11, or to facilitate manufacture of the package, the flaps 10 forming each side wall, may be secured together by a strip 12 of adhesive 15 paper or the like.

The lower end of each wall 8 and 9 is provided with a flap 12, which flaps in turn extend toward one another to form the bottom of the box, and are provided with upwardly extending end flaps 13 which are secured to the flaps 10 by any suitable means, such as staples 14.

Each flap 12 is bent upwardly, as shown at 15, to form spaced short vertical walls defining a bottom delivery opening, and these walls are 25 integral with downwardly diverging strips 16 which in turn are integral with re-entrant flaps 17 that are secured to the flaps 12 by any suitable means such as staples 18. The parts 15 and 16 form triangular ridges extending across 30 the box at either side of the delivery opening and the peaks of the ridges are relatively narrow to support the central sagging portion of the towels in the stack.

As heretofore mentioned, the distance between 35 the walls 8 and 9 is less than the width of the stack 5, and as this exerts pressure on the towels they are caused to sag downwardly at the center. Each of the walls 8 and 9 is provided at its inner surface with a reinforcement or friction means 40 19 preferably consisting of a sheet of corrugated fiberboard of about the same width as the wall to which it is secured, and as the corrugations of these sheets are horizontally arranged and engage the folded edge portions 20 of the towels 45 (Fig. 3), it will be obvious that these sheets act to support the stack and thereby take the weight of the stack off of the lowermost sheet. This coupled with the line support of the sagging center portions of the lowermost towels by the 50 ridges 15, 16, facilitates the withdrawal of the towels without danger of tearing them.

As it is necessary in withdrawing a towel to bend it over the edges of the delivery opening, it is of primary importance that the top of the ridges 55

adjacent the delivery opening be straight and have no sag, as a sheet being withdrawn over a deflected or sagged lip of a delivery slot would wrinkle and cause undue tension necessary for its withdrawal. That is the reason why we make the ridges of triangular cross section as such construction acts to reinforce the ridges.

As the box is made to function as a delivery cabinet, tongues 21 may be punched in the rear wall to allow the box to be suspended on a wall 22 by means of nails 23 or the like.

Instead of using corrugated paper sheets 19, heavy creped paper may be used as frictional means.

13. The bottom or delivery opening of our improved box may be formed by simply bending the board upon itself. It may be rolled and bent upon itself to provide a ridge or the triangular formation which is illustrated and used to stiffen the 20 delivery edges may be altered to form a funnel shaped opening.

While we have disclosed what we now consider to be a preferred embodiment of the invention in such manner that the same may be readily understood by those skilled in the art, we are aware that changes may be made in the details disclosed without departing from the spirit of the invention as expressed in the claims.

What we claim and desire to secure by Letters 30 Patent is:

1. A package of paper towels or the like comprising a box of stiff material having a delivery opening at its bottom, a stack of superimposed interfolded paper towels arranged in the box, opposite side walls of the box being spaced apart a less distance than one dimension of the stack whereby the towels of the stack are caused to sag at the center, and straight ridges at the bottom of the box arranged at either side of the delivery opening and forming line contact supports for the sagging center portions of the lowermost towels of the stack.

2. A package of paper towels or the like comprising a box of stiff material having a delivery 45 opening at its bottom, a stack of superimposed interfolded paper towels arranged in the box, opposite side walls of the box being spaced apart a less distance than one dimension of the stack whereby the towels of the stack are caused to sag 50 at the center, and straight ridges at the bottom of the box arranged at either side of the delivery opening and forming line contact supports for the sagging center portions of the lowermost towels of the stack, the inner surface of each of said 55 walls of the box being provided with friction means engaging the folded edges of towels of the stack to retard descent of the towels.

3. A package of paper towels or the like comprising a box of stiff material having a delivery 60 opening at its bottom, a stack of superimposed

interfolded paper towels arranged in the box, opposite side walls of the box being spaced apart a less distance than one dimension of the stack whereby the towels of the stack are caused to sag at the center, and straight ridges at the bottom of the box arranged at either side of the delivery opening and forming line contact supports for the sagging center portions of the lowermost towels of the stack, each of said side walls being provided at its inner surface with horizontally arranged corrugations forming ledges on which the folded edge portions of the towels of the stack rest.

4. A package of the character described comprising a receptacle having fixedly arranged relatively stiff parallel opposite side walls and a bottom delivery opening, a stack of interfolded paper towels arranged in the receptacle, friction means arranged on the inner surface of each of said walls and engaging opposite sides of the stack to retard the movement of the towels downwardly toward the delivery opening, and straight ridges projecting upwardly from the bottom of the receptacle at opposite sides of the delivery opening and forming line contact supports for the lowermost towels of the stack.

5. A shipping and dispensing container for paper towels or the like provided with a bottom delivery opening, and inwardly and upwardly projecting lips bounding opposite sides of the delivery opening.

6. A non-refillable shipping and dispensing container formed of fibrous material, and comprising two opposed walls having roughened inner surfaces, two opposed walls having smooth surfaces, 35 a bottom provided with a delivery slot, and upwardly extending lips arranged on the bottom at opposite sides of the slot and provided with means for increasing the rigidity thereof.

7. A package of the character described comprising a fiberboard container having a delivery opening, and a stack of interfolded paper towels arranged in the container for delivery of the towels through said slot, two opposing walls of the container normally exerting sufficient frictional contact on the stack to cause a sag of the portion of the stack toward the delivery end between the folded edges of the towels, and inwardly extending lips provided at either side of the delivery slot and forming supports for the sagging portion of the stack.

8. A package of the character described comprising a fiberboard box provided at its bottom with triangular shaped ridges which extend across the bottom of the box and define a delivery opening, and a stack of interfolded paper towels arranged in the box and having a portion resting on said ridges.
